Geo. Kirk

ATTORNEY

UNITED STATES PATENT OFFICE.

JOHN D. SILBERZAHN, OF TOLEDO, OHIO.

FLY-WHEEL.

1,177,824.

Specification of Letters Patent.

Patented Apr. 4, 1916.

Application filed September 21, 1912. Serial No. 721,539.

To all whom it may concern:

Be it known that I, JOHN D. SILBERZAHN, a citizen of the United States, residing at Toledo, Lucas county, Ohio, have invented 5 a new and useful Fly-Wheel, of which the following is a specification.

This invention relates to air current generating means especially adapted for cooling purposes.

10 This invention has utility when embodied in fly wheels of internal combustion engines.

Referring to the drawings: Figure 1 is a perspective view of an embodiment of the invention in a single cylinder internal combustion engine; Fig. 2 is an inner side elevation of one of the fly wheels embodying the invention; and Fig. 3 is a medial transverse section of the fly wheel of Fig. 2.

The internal combustion engine is shown 20 as having but the single cylinder provided with heat radiating ribs 1. This engine of the reciprocating type has extending from the combustion chamber or cylinder, the connecting rod 2 engaging the crank 3 of 25 the shaft 4 carrying in this instance the pair of fly wheels 5. These fly wheels 5 are shown as provided with radiating vanes 6, 7, adjacent their peripheries forming therebetween air circulation pockets 8. Certain 30 of the vanes 7, herein shown as three in number, are of greater mass than the other vanes 6. These vanes 7 are of sufficient weight to serve as counterbalances for the reciprocating parts, to effect which they are 35 disposed diametrically opposite to the crank 3 of the shaft 4 upon which the flywheels 5 are mounted. The device to be driven by the engine may be directly connected to the shaft 4, or by pulley thereon, as desired.

40 In operation, the pockets 8 entrain air, which in the rotation of the wheels 5 tends by its gravity to be thrown radially. The concave or dishing form of these pockets 8 allows the air entering on the inner open 45 side to work outwardly, but the curve in the pocket walls adjacent the inner side of the fly wheel rims, deflects this air for lateral discharge. With the vaned side of the fly wheel toward the heat radiating ribs of 50 the combustion chamber inclosing cylinder, these air currents from the fly wheel effect continuous change of atmosphere about the

ribs 1, and consequently preclude any air adjacent said ribs being warmed to any great extent. With the vaned fly wheels opposed 55 to each other, as shown in Fig. 1, any cylinder or cylinders in the range therebetween have air currents continually all about them, insuring effective cooling throughout.

The device is simple, involving no extra 60 working parts whatever, and due to its simplicity, the slight air resistance of the fly wheel fans is not such as to detract from the total efficiency of the motor, due to air cooling. With no parts to get out of order, 65 and all the features of the cooling device exposed, a most desirable air cooled internal combustion engine is economically produced embodying the device of this disclosure.

What is claimed and it is desired to secure 70 by Letters Patent is:

1. A flywheel provided with vanes adjacent its periphery, said vanes partially forming intermediate their extent within the planes of the periphery of the wheel 75 dished pockets to circulate air during rotation of the flywheel.

2. A flywheel, a cranked shaft on which the wheel is mounted, said flywheel having, on the side thereof toward the crank of 80 the shaft, vanes partially forming intermediate their extent within the planes of the periphery of the wheel concave pockets to circulate air during rotation of the flywheel.

3. A flywheel provided with an annular series of air actuating vanes, said vanes eccentrically weighting said flywheel.

4. A flywheel provided with a rim, air 90 circulating vanes radially extending from said rim, said vanes partially forming intermediate their radial extent within the planes of the periphery of the wheel dished pockets for laterally deflecting radially moving air during rotation of the 95 flywheel.

5. A flywheel provided on one side thereof with a plurality of concavities opening toward said side, said concavities being adjacent the periphery of the flywheel and forming an endless series of air circulation 100 pockets within the planes of the periphery of the wheel.

6. A flywheel having a rim, supporting

means for the rim, said rim being dished on its inner side, and vanes extending inwardly from said rim in addition to and independently of the rim supporting means.

5 7. A flywheel provided with eccentrically weighting air circulating vane means.

8. A flywheel provided with an annular series of air circulating vanes uniformly dis-

posed, a plurality of said vanes being configured to eccentrically weight the wheel. 10

In witness whereof I affix my signature in the presence of two witnesses.

JOHN D. SILBERZAHN.
